ELECTRIC CLOCK MECHANISM

John Zubek, Detroit, Mich.

Application December 13, 1938, Serial No. 245,510

1 Claim. (Cl. 185—40)

The objects of this invention are to provide a novel means for driving the time train of a clock electrically, and to provide a specifically novel structure for attaining that result, other objects being made manifest as the description proceeds.

A mechanic who gives heed to what is claimed, may alter the precise structure shown, without departing from the spirit of the invention.

Fig. 1 shows in elevation, a device constructed in accordance with the invention;

Fig. 2 is an elevation wherein the device is viewed edgewise;

Figs. 3, 4 and 5 are elevations showing different positions of the parts;

Fig. 6 is a detail enlarged from Fig. 2, parts having been removed;

Fig. 7 is a section on the line 7—7 of Fig. 3.

Electro-magnets 1 are carried by a shelf 2, secured to a support or plate 3, and an armature 4, hingedly mounted at 5 on the support, responds to the electro-magnets and overcomes the effort of a pull spring 6, connected to the intermediate portion of the armature and to a bracket 7 on the support, a depending rod or pawl 8 having its upper end pivoted at 9 to the armature, the rod being supplied adjacent to its lower end with a lateral lug 10, the rod terminating in a reduced and inwardly inclined finger 11.

A ratchet wheel 12 is secured to a shaft 14, 30 journaled in the support 3, and forming part of the time train 15 of a clock. For convenience in setting forth the operation hereinafter, the ratchet wheel 12 may be said to comprise a group of teeth *a*, *b*, *c* and *d*, and each tooth may be said 35 to include a radial shoulder 16 and an inclined edge 17. The lug 10 of the rod 8 is adapted to engage under the shoulder 16 of any tooth of the ratchet wheel 12, the finger 11 of the rod extending between the ratchet wheel and the support 3.

Three spring tongues, marked 18, 19 and 20, have their lower ends secured, by any appropriate means 21, to the support 3. The tongue 18 may be denominated a pawl-throw, the tongue 20 a first switch member, and the tongue 19 a second switch member. The tongue 18 terminates at its upper end in an outwardly inclined tip 22, and the tip merges into an inwardly extended projection 23 on the tongue 18. The tongue 19 is shorter than the tongue 18 and it carries an uninsulated switch point 24, adapted to engage an insulated switch point 25 on the tongue 20, the tongue 20 being longer than the tongue 19 and shorter than the tongue 18.

The anchorage means 21 for the lower ends of

the tongues 18, 19 and 20 is in electrical engagement with the support 3, and to said means is joined a conductor 26, connected to one side of a source 27 of electrical energy. To the opposite side of the source 27 is connected a conductor 28, 5 wherein is interposed a switch 29, under the control of an operator, the conductor 28 being joined to the winding 30 of the electro-magnets 1, the winding being connected to a conductor 31, joined to the insulated switch point 25 on the tongue 20.

When the parts are arranged as shown in Fig. 3, the lug 10 on the rod 8 is below the shoulder of the tooth *a* of the ratchet wheel 12, the switch points 24 and 25 being in contact. Then there is established an energizing circuit for the electro-magnets 1, including the source 27, the conductor 28, the (closed) switch 29, the winding 30, the conductor 31, the insulated switch point 25 on the tongue 20, the switch point 24, the tongue 19, the support 3, and the conductor 26: all of which will be understood when Fig. 3 is compared with Fig. 1.

The circuit for the electro-magnets 1 thus being closed, the electro-magnets are energized, the armature 4 is attracted, and the rod 8 is carried downward. Referring to Fig. 3, as the lug 10 on the rod 8 moves downwardly, the lug is guided along the tip 22 of the tongue 18 until the lug 10 slides downwardly along the inclined edge 30 of the tooth *b*, the rod 8 then being carried to the left, and the tongue 18 being carried to the left as the lug 10 on the rod 8 moves downwardly over the projection 23 on the tongue 18.

As the rod 8 moves downwardly, a time arrives 35 when the upper surface of the lug 10 on the rod 8 is flush with the shoulder of the tooth *b*, and, due to the thrusting action of the tongue 18 to the right, the rod 8 is swung to the right on its pivotal mounting 9, the lug 10 being carried beneath the shoulder of the tooth *b*, as in Fig. 4. When the rod 8 moves to the right, the finger 11 on the rod engages the tongue 20 and flexes that tongue, the switch point 25 being spaced from the switch point 24, and the circuit of the 45 electro-magnets 1 thus being opened.

When the parts are arranged as shown in Fig. 4, there is no downward electro-magnetic drag on the armature 4, and the pull spring 6 gets in its work, the armature being swung upwardly on its hinged mounting 5, the rod 8 being raised, and the lug 10 on the rod cooperating with the shoulder on the tooth *b*, to turn the ratchet wheel 12 one step, rotate the shaft 14, and actuate the time train 15 accordingly.

Referring to Fig. 5, it will be seen that, upon the upward movement of the rod 8, the lug 10 on the rod moves out of contact with the tip 22 of the tongue 18, and the tongue 18 is set free to assume its normal position. The tongue 20, also, is permitted to assume its normal position, because that tongue no longer is held to the right by the finger 11 of the rod 8. Although the restoring of the tongue 20 to a normal position 10 is desirable, such an operation, in the absence of a feature to be described hereinafter, would engage the switch point 25 with the switch point 24, close the circuit of the electro-magnets 1, and cause them to exert a downward pull on the armature 4, before the upwardly-acting spring 6 had accomplished all that is required of it.

The aforesaid premature energizing of the magnet circuit is prevented, because, as the ratchet wheel 12 turns, the point of the tooth *d* engages 20 the tongue 19 and flexes the said tongue to the left, as in Fig. 5, thus keeping the switch points 24 and 25 spaced, notwithstanding the fact that the tongue 20 has swung back to the left, to its normal position. Ultimately, the point of the tooth *d* clears the upper end of the tongue 19, the tongue 19 swings to the right in Fig. 5, the switch points 24 and 25 are brought together, and the parts are restored to the position of Fig. 3.

30 By the use of the device forming the subject matter of this application, the gearing of a clock can be reduced to a simple time train, comprising no more than a few gear wheels and associated parts. The market has many starting devices which, if desired, may be added to the structure herein set forth, the special starting mechanism being something with which the present application is not concerned.

Although not confined to such a use, the device 40 described (costing less than seventy-five cents in the present state of trade) can be combined with a dollar clock, from which most of the works

have been removed, and the result will be a good, electrically-operated timepiece.

The rod 8 functions as a pawl, the tip 22 as a guiding part for the pawl, and the spring 6 as a resilient means for actuating the pawl to 5 cause the pawl to rotate the ratchet wheel 12. The spring tongue 18 functions as a pawl-throw. The tongues 19 and 20 constitute a normally-closed switch, whereof the tongue 20 is the first member and the tongue 19 is the second member. 10

What is claimed is:

A driving mechanism comprising a circuit, an electro-magnet in the circuit, a switch in the circuit and including first and second members cooperating resiliently to close the circuit when in normal positions, a rotatable ratchet wheel including teeth each having an inclined edge and a shoulder, a resiliently-acting pawl-throw, an armature responsive to the magnet, a pawl actuated by the armature to cause the pawl to move along the inclined edge of one tooth, displace the pawl-throw from normal position, and render it active, the pawl-throw reacting to normal position and engaging the pawl with the shoulder of said tooth, the pawl cooperating with the first 25 switch member to displace it from normal position and open the circuit, resilient means for operating the pawl to cause it to rotate the wheel whilst the circuit is open, and to cause the pawl to free itself from the pawl-throw and permit the first switch member to return to normal, circuit-closing position, another tooth meanwhile engaging the second switch member and holding the switch open when the first switch member moves to normal, circuit-closing position, thereby 30 enabling the resilient means to complete its operation whilst the circuit is open, the rotation of the wheel causing said other tooth to clear the second switch member and permit it to return to normal position and to circuit-closing 40 relation with respect to the first switch member.

JOHN ZUBEK.
